UNITED STATES PATENT OFFICE.

LOUIS SAMTER, SAMUEL L. SAMTER, AND HENRY PINNER, OF SAN FRANCISCO, CALIFORNIA.

COMBINATION-NECKTIE.

SPECIFICATION forming part of Letters Patent No. 722,633, dated March 10, 1903.

Application filed June 27, 1902. Serial No. 113,384. (No model.)

To all whom it may concern:

Be it known that we, LOUIS SAMTER, SAMUEL L. SAMTER, and HENRY PINNER, citizens of the United States, and residents of the city and county of San Francisco and State of California, have invented a new and useful Improvement in Combination-Neckties, of which the following is a specification.

This invention has for its object to provide an article of neckwear that is convertible into a puff-scarf or Teck tie and in which the parts that form one also go to produce the other style of tie; and the invention consists in certain novel construction and combination of neck-piece, loop, and scarf members, as hereinafter explained in the following description, in which the accompanying drawings are referred to by letters.

Figure 1 is a front view representing our combination-tie arranged as a scarf. Fig. 2 represents the same converted into a Teck tie. Fig. 3 shows the parts that go to make up the complete tie. Fig. 4 is a top view of the neck-piece and the loop. Fig. 5 is a modification in which the neck-piece is composed of a strap.

The parts comprising our improved tie are herein designated and referred to as the neck-piece *a*, the loop *b*, and the scarf portion *c*. In one form the neck-piece is constructed to be worn with a turn-down collar, and it consists of a stiff piece shaped to fit the curvature of the neck at the front, resembling generally the curved back piece of a butterfly bow or a made-up bow-knot. Such part is usually made by cutting a strip of cardboard or similarly stiff material to the required outline and covering it with a piece of the same fabric as the scarf. In another form the neck-piece is adapted to secure the tie in place on the wearer with a standing collar, and for that purpose the neck-piece consists of a strap *a* of proper length to pass around the neck on the outside of the collar like the strap

usually provided on a Teck tie or a ready-made bow-knot. On the front of this part is fixed the loop *b*, which is similarly composed of a stiff frame or foundation covered with the fabric and is open at both ends. At the junction of the parts *a* and *b*, where the top of the loop joins the frame, the scarf portion *c* is attached by one end, so as to leave the body or main portion unattached and free to be inserted in and drawn through the loop *b*. The fabric employed for this part *c* should be of soft and flexible quality to form graceful folds, as well as to be drawn easily through the loop. It should be of proper width also to produce or form the scarf when it is brought over the loop and gathered in folds, as shown in Fig. 1, and it may be lined for the whole or a portion to give desirable stiffness at portions of the scarf when it is made of very light or thin fabric. This lining or stiffening is usually provided at the upper portion, where the scarf is gathered in folds or plaits. As thus produced, it will be seen that the article is changed from one style of scarf or tie by inserting the unattached end of the scarf portion in the top end of the loop and drawing the same downward through the loop until the part attached to the frame above the loop stands in folds outside the loop. By this adjustment the article forms the tie illustrated in Fig. 2. When the other style of tie is desired, the part *c* is drawn out of the loop and brought over in loose folds, forming what is commonly known as a "puff." In that position the loop is concealed and also constitutes a foundation or filling that tends to keep the puff in shape.

Having thus fully described our invention, what we claim as new, and desire to secure by Letters Patent, is—

1. A combination-tie comprising a neck-piece adapted to secure the tie in place on the wearer, a loop on the neck-piece and a scarf portion attached to the neck-piece and adapt-

ed in one position to cover the loop and form a puff-scarf, and in the other position to lie within the loop and be held in place by that part.

- 5 2. In a combination - tie the combination with a neck-piece adapted to secure the tie in place on the wearer, a loop attached to said neck-piece and the adjustable scarf portion also attached to the neck-piece and adapted to in one position to cover and conceal the loop, and in the other position to lie within and be clasped by the loop.

In testimony whereof we have signed our

names in the presence of two subscribing witnesses.
